UNITED STATES PATENT OFFICE.

CARL S. STAUGAARD, OF CHICAGO, ILLINOIS.

DESIGN FOR A RADIO CABINET PANEL.

Application filed September 27, 1926. Serial No. 19,185. Term of patent 7 years.

To all whom it may concern:

Be it known that I, CARL S. STAUGAARD, a citizen of the United States, residing at Chicago, in the county of Cook and State of Illinois, have invented a new, original, and ornamental Design for Radio Cabinet Panels, of which the following is a specification, reference being had to the accompanying drawing, forming part thereof.

As shown in these drawings;
Figure 1 is a front view of a radio panel showing my new design; and
Figure 2 is a longitudinal sectional view of the same.

I claim:
The ornamental design for a radio cabinet panel, as shown.

CARL S. STAUGAARD.
